UNITED STATES PATENT OFFICE.

JOHN H. SHAW, OF NEW HAVEN, CONNECTICUT.

WALKING TOY.

1,332,072.

Specification of Letters Patent. Patented Feb. 24, 1920.

Application filed February 10, 1919. Serial No. 276,133.

To all whom it may concern:

Be it known that I, JOHN H. SHAW, a citizen of the United States, residing in the city and county of New Haven, State of Connecticut, have invented certain new and useful Improvements in Walking Toys, of which the following is a full, clear, and exact description.

This invention relates to a walking toy and more particularly to a doll or the like constructed to simulate more or less accurately the walk of a human being, although it will be apparent that the mechanism herein disclosed may equally as well be applied to toy animals.

The normal walk of a human being consists in supporting the weight of the body upon one leg while the other leg is swung to a forward position, the free leg while moving to its forward position being bent at both the knee and ankle sufficiently to clear the ground as it passes the leg supporting the weight of the person. The difficulty of providing a simple but satisfactory walking toy is due to the fact, that unless the toy is swung from side to side sufficiently to permit first one leg to be advanced and then the other, some means must be provided to permit one leg to be swung to the advanced position without striking the surface upon which the leg supporting the weight of the toy rests.

The primary object of my invention is to provide a walking toy with means whereby while the weight of the toy is supported upon a surface by one leg, the other leg may be swung from a rear to a forward position without requiring the toy to be rocked transversely.

A more specific object of my invention is to provide a walking toy with pivoted legs, each of which is provided with gravity controlled means for automatically varying the overall length of each leg, whereby the leg which supports the weight of the toy will for that instant possess a greater overall length than the leg which is swinging past the same.

Another object of my invention is to provide a novel arrangement of resilient means for swinging the pivoted legs to a forward position.

To these and other ends, the invention consists in the novel features and combinations of parts to be hereinafter described and claimed.

In the accompanying drawings:

Figure 1 is a side view of a toy doll, shown partly cut away to illustrate my invention applied thereto, the left leg being shown advanced and the weight resting upon the right leg.

Fig. 2 is a view similar to Fig. 1, showing the position of the gravity controlled means when the step which is being taken by the left leg in Fig. 1 has been partly completed, the weight of the toy in this figure being supported by the left leg, while the right leg is in position to be swung to its advanced position.

Fig. 3 is a view similar to Figs. 1 and 2, showing the position of the gravity controlled means after the right leg, (Fig. 2) has been swung forward to a position slightly in advance of the vertical position.

Fig. 4 is an enlarged sectional view of part of the mechanism shown in Fig. 1.

Fig. 5 is an enlarged front view of part of the trunk or body of the toy showing the legs pivotally secured thereto.

Fig. 6 is an enlarged longitudinal sectional view of one foot of the walking toy having the gravity controlled means applied thereto.

Fig. 7 is a sectional view taken on line 7—7 of Fig. 6.

Fig. 8 is a view similar to Fig. 6 showing a modification of my invention; and

Fig. 9 is a sectional view taken on line 9—9 of Fig. 8.

In the embodiment of my invention, illustrated in the drawings, I have shown a toy doll having a one piece head and body or trunk designated by the numeral 10, and having legs 11 and 12 pivotally secured to the trunk 10, in a manner hereinafter more fully pointed out. Although I have illustrated my invention in connection with a toy doll, I desire to have it distinctly understood that my novel walking mechanism herein disclosed may readily be applied to various types of toys provided with either two or four legs.

The means which I have illustrated for pivotally securing the legs 11 and 12 to the trunk 10 consists in providing the trunk 10 at its lower end thereof with spaced concaved sockets 13 adapted to receive the upper rounded ends of the legs 11 and 12, and centrally positioned in each of these sockets is a downwardly projecting post 14, the upper end of which is preferably rigidly

mounted in a drill-hole 15 extending upwardly within the trunk 10, the lower portion of the post 14 is preferably substantially rectangular in cross-section and is 5 adapted to be loosely received in a relatively wide saw cut 16 formed in the upper end of each of the legs 11 and 12, the legs being pivotally secured to the lower portion of the post 14 by pins 17, which extend trans- 10 versely through the upper end of the leg and through the post, as will be apparent from Figs. 4 and 5. In order that the legs may swing freely upon their pivotal mounting, just mentioned, the parts should be so constructed that the lower portion of the post 14 will be loosely received in the slot 16 and the upper end of the legs 11 and 12 should at all times clear the sockets 13 which receive the same. In most embodiments of 15 my invention, it is desirable to provide means for automatically advancing each leg from its rear to its forward position as soon as the weight of the toy has been removed from the same, this, however, is not an essential feature in all embodiments of 20 my invention, since it will be apparent that my toy will walk down an inclined plane without this leg advancing means, as the force of gravity alone will be sufficient to 25 swing the legs to their forward position as soon as they are disengaged from the surface upon which the toy stands. The leg advancing means which I have illustrated in the drawings consists in providing a substantially 30 U-shaped wire spring 18, which is mounted in a saw cut 19 formed in the rear face of the lower portion of the post 14. The spring 18 may be conveniently retained in its proper position within the post 35 14 by bending one end of the same in an outward direction, as at 20, which end is mounted in a drill-hole formed in the post 14. The other end 21 of the U-shaped member 18 reacts against the bottom of the 40 saw cut 16 formed in the upper end of the legs at a point above the horizontal plane of the pivot pin 17, the arrangement being such that the reaction of the end 21 of the 45 spring 18 against the upper end of the pivoted legs 11 and 12 tends to swing the legs about their pivot 17 to a forward position, as will be apparent.

As above pointed out, in order to provide a walking toy which will simulate the walk 50 of a person or animal, it is necessary to provide some means whereby while the weight of the toy is supported upon one leg, the other leg will be permitted to swing past the same without striking the surface upon 55 which the weight supporting leg stands. The means which I have provided for this purpose consists in slidably mounting a roller or the like 22 in the bottom of each foot, the same being constructed and arranged to move back and forth in a longi-

tudinal direction within each foot along an inclined path so that when the roller is moved to its rearmost position, as shown in full lines in Fig. 6, the same will be partly exposed below the lower face or sole of the 70 foot, and when the roller 22 is moved along its inclined path within the foot to its forward position, it will be entirely housed in the same, as indicated in dotted lines in this figure. One convenient means of mounting 75 the roller 22 so that it will operate in the manner just set forth is to provide this roller with a relatively short stub shaft 23 extending centrally from the opposite sides thereof, which forms an axle to guide the 80 roller back and forth along the inclined track formed by the spaced wires 24 and 25. The wire 24 preferably has the configuration of a hairpin or of the letter U with relatively long legs, the end of which legs are 85 driven into the toe of the foot, as indicated at 26. The wire guiding means 25 may be similarly formed, except that the rounded portion of this U-shaped member is bent at right angles to the relatively long legs, as 90 at 27, so that this bent portion 27 will abut against the spaced wires 24 near the rounded end of the same, as shown in Fig. 6, whereby the guide wires 24 and 25 may be retained in spaced relation, so that the axle 95 or stub shaft 23 upon the roller 22 may move freely back and forth between these parallel spaced wires. The looped end of the spaced wires 24 and 25 are preferably secured in place by the L-shaped pin or staple 28, 100 which may be driven into the heel of the foot, as shown, with the head of this staple in engagement with one end of the wires 24 and 25, the other end of the spaced wires 25 are preferably driven into the toe of the 105 foot, as indicated by 26'. The spaced U-shaped wires 24 and 25 are so positioned within a slot 29 formed in the bottom of each foot, that when the roller 22 is moved to its rearmost position, it is exposed below 110 the bottom of the foot, and when moved to the other end of its path of travel, it is entirely housed within the foot, as above stated.

The operation of my device is as follows, 115 particular reference being had to Figs. 1, 2 and 3 of the drawing. When the right leg is in the vertical position shown in Fig. 1 of the drawing, the foot will be held out of engagement with the surface 29 by the 120 roller 22, as shown, and the roller 22 in the left leg 12 lies partially exposed below the bottom of the foot, as shown in this figure, the same having been moved to this position by the force of gravity, as the foot is moved 125 by the spring 18 to the advanced position here shown. Turning our attention to Fig. 2, as the toy is moved forward preferably by grasping the same and imparting a forward movement to the same, the body of the 130

toy will be moved in a forward direction relatively to the leg 11 upon which the weight of the same is supported, this leg being swung about the pivot pin 17, so that 5 it gradually assumes a rearward position, while at the same time the toy moves downwardly slightly toward the supporting plane 29, this being due to the fact that the leg 11, although still supporting the 10 weight of the toy, does not lie in a vertical position, so that upon further movement of the toy in a forward direction the heel of the left leg 12 will come into contact with the plane 29 and immediately thereafter the 15 weight of the toy will be transferred to this leg and will be supported by the roller 22 mounted in the foot of the same. As soon as the weight of the toy is removed from the right leg, the roller 22, due to the force of 20 gravity, will roll down its guide way to the position shown in dotted lines in Fig. 2, whereupon this right leg may then be freely swung to its forward position by its spring 18 without contacting with the surface 29, 25 the roller 22 remaining completely housed within the foot until the same has swung past its vertical position, as indicated in Fig. 3 of the drawing, but as this right leg continues to move forwardly, the roller 22 30 will be moved by the force of gravity toward the heel of the foot in position to again engage the plane 29 and support its foot out of contact with the same. In order to prevent the roller 22 from moving prematurely along its inclined path, a notch 35 30 is preferably cut in the opposite spaced wires 24 to receive the axle 23 of the roller and likewise, if desired, a similar notch 31 may be formed in the spaced wires 25 to receive the axle 23 and thereby prevent the roller from being prematurely moved from the toe toward the heel of the foot. Both the heel and the toe of the foot are preferably rounded, as shown in Fig. 6 of the 40 drawing.

In Figs. 8 and 9 of the drawing, I have shown a modification of the structure illustrated in Figs. 6 and 7. In the modification, I have shown a ball or roller 22', which is 45 slidably mounted in a tube 32, which is mounted in a socket or drill-hole formed in the bottom of the foot and inclining toward the toe away from the sole of the same. The tube 32 is partially cut away, as indicated at 33, in order to partially expose the ball 22', as it is moved by gravity from its forward to its rearward position. The rear end of the tube 32 is preferably secured in place by a screw 34, the head of which 50 serves as means for preventing the ball 22' from passing the same and thereby escaping from within its tube 32. From the above description, it will be apparent that I have 55 devised a walking toy, which when the same is grasped and moved along a surface, pref-

erably not too smooth, the toy will walk in a natural manner, supporting its weight upon one foot, while the other swings freely past the same without requiring the toy to be rocked in a horizontal direction to permit the legs to swing to their forward position. 70

Since the foregoing description is necessarily a detailed one, it will be apparent that various changes may be made in the device 75 herein disclosed without departing from the spirit of my invention, as defined in the annexed claims.

What I claim is:

1. A walking toy having legs pivotally secured to the body thereof, feet upon said legs, gravity operated members mounted within said feet and automatically movable into and out of the plane of the bottom of said feet, whereby while one leg supports 80 the weight of the toy the other leg and the gravity operated member carried thereby may swing past the weight-supporting leg without striking the surface upon which the toy walks. 90

2. A walking toy having legs pivotally secured to the body thereof, feet upon said legs, and means for permitting one leg to swing freely from its rear to its forward position without striking the surface upon 95 which the toy is supported by the other leg, comprising a supporting member slidably mounted in each foot and movable into and out of the plane of the bottom of said foot by the force of gravity. 100

3. A walking toy having legs pivotally secured to the body thereof, feet upon said legs, and means for permitting one leg to swing freely from its rear to its forward position without striking the surface upon 105 which the toy is supported by the other leg, comprising a supporting member mounted within each of said feet and constructed to move along an inclined path within said feet toward and from the bottom of the 110 same.

4. A walking toy having legs pivotally secured to the body thereof, feet upon said legs, and means for permitting one leg to swing freely from its rear to its forward 115 position without striking the surface upon which the toy is supported by the other leg, comprising a roller mounted in each of said feet and movable into and out of the plane of the bottoms of said feet by the force of 120 gravity. 120

5. A walking toy having legs pivotally secured to the body thereof, feet upon said legs, and means for permitting one leg to swing freely from its rear to its forward 125 position without striking the surface upon which the toy is supported by the other leg, comprising a supporting roller movably mounted in each foot, constructed to be completely housed within its foot when the foot 130

is swung to its rearmost position, and to automatically move therefrom to an exposed position as the foot is swung toward its advanced position.

5. A walking toy having legs pivotally secured to the body thereof, feet upon said legs, and means for permitting one leg to swing freely from its rear to its forward position without striking the surface upon

10 which the toy is supported by the other leg, comprising a roller movably mounted in each foot and constructed to travel along an inclined path whereby when said roller is moved to its rearmost position it will lie 15 partially exposed below the bottom of the foot, and when moved to its forward position said roller will be completely housed within said foot.

6. A walking toy having legs pivotally secured to the body thereof, feet upon said legs, and means for permitting one leg to swing freely from its rear to its forward position without striking the surface upon which the toy is supported by the other leg, 25 comprising a supporting member slidably mounted in each foot, means within each foot for guiding said supporting means along an inclined path relatively to the bottom of the foot, whereby said supporting 30 means when moved to its rearmost position is partially exposed and when moved to its advanced position is entirely housed within said foot.

7. A walking toy having legs pivotally secured to the body thereof, feet upon said legs, and means for permitting one leg to swing freely from its rear to its forward position without striking the surface upon which the toy is supported by the other leg, 40 comprising a toy supporting member slidably mounted in each foot, means for guiding said member along a path inside of said feet inclined at an angle to the sole of the same whereby said member is exposed below 45 the sole of said foot when in one position and is entirely housed within said foot when in a second position, and means for preventing a premature movement of said supporting member from one end of its path of 50 travel to the other.

8. A walking toy having legs pivotally secured to the body thereof, feet upon said legs, means tending to automatically swing said legs to their forward position, and supporting means movably mounted in each of 60 said feet, said supporting means constructed and arranged to be moved to and from the interior of said feet by the force of gravity.

9. A walking toy having legs pivotally secured to the body thereof, feet upon said legs, resilient means for swinging said legs forwardly relatively to said body, and

gravity controlled means mounted within said feet and movable bodily into and out of the interior of the same whereby the 65 overall length of said legs is automatically varied.

10. A walking toy having legs pivotally secured to the body thereof, feet upon said legs, supporting means slidably mounted in 70 said feet, said supporting means constructed to be moved by gravity into and out of the interior of said feet whereby the overall length of said legs is automatically decreased and increased. 75

11. A walking toy provided with a body and legs pivotally secured thereto, spaced leg supporting means rigidly secured to said body member, a leg pivotally mounted upon each of said supporting means, and resilient 80 means for automatically swinging said legs to their advanced position, comprising a spring housed within each of said leg supporting means and having one end projecting therefrom into position to react against 85 the leg pivotally secured to the supporting means in which it is housed.

12. A walking toy having legs secured to the body thereof, feet upon said legs, and gravity controlled means carried by said 90 feet, said means constructed and arranged to be moved by gravity into and out of position to project from the bottom of said feet.

13. A walking toy having legs pivotally secured to the body thereof, feet upon said legs, and gravity controlled means carried by said feet, said means constructed and arranged to be moved by gravity into and out of 95 position to project from the bottom of said feet.

14. A walking toy having legs pivotally secured to the body thereof, feet upon said legs, and gravity operated means carried by said feet, said means constructed and arranged to move into the interior of each 100 foot as the foot is moved to one position and to protrude therefrom as the foot is moved to another position. 105

15. A walking toy having legs pivotally secured to the body thereof, supporting means movably carried by each of said legs, 110 said supporting means constructed and arranged to be moved by the force of gravity to and from a position to protrude from said legs.

16. A walking toy having legs secured to the body thereof, feet upon said legs having longitudinal slots formed in the bottoms thereof, rollers slidably mounted within said slots and movable therein to and from a position to protrude from the bottoms of 115 said feet, said rollers having stub shafts projecting from the opposite sides thereof, and means within said slots constructed to engage said shafts to retain said rollers within said slots. 120

In witness whereof, I have hereunto set my hand on the 7th day of February, 1919.

JOHN H. SHAW.
